J. G. HOLLINGSWORTH

DENTAL OCCLUSIAL DEVICE

Filed May 1, 1922

UNITED STATES PATENT OFFICE.

JEPHTHA G. HOLLINGSWORTH, OF KANSAS CITY, MISSOURI.

DENTAL OCCLUSIAL DEVICE.

Application filed May 1, 1922. Serial No. 557,514.

To all whom it may concern:

Be it known that I, JEPHTHA G. HOLLINGSWORTH, a citizen of the United States, and resident of Kansas City, Jackson County, Missouri, have invented a certain new and useful Improvement in Dental Occlusial Devices, of which the following is a complete specification.

This invention relates to a method of articulating upper and lower sets of artificial teeth in the mouth of a patient and to dental occlusial devices for use in such methods, and my object is to provide for expeditiously and economically equipping a patient with a complete set of properly articulated artificial teeth with the least possible annoyance to the patient and without putting the operator to the trouble of adjusting the teeth with respect to each other, the course or method now followed by dentists and prothesis who employ articulators of various types in their work.

A further object is to produce an occlusal device by which upper and lower sets of teeth can be simultaneously adjusted forward, backward or laterally in the mouth of the patient to enable the latter by consulting a mirror, to see the effect produced with the mouth closed and opened and hence decide in what position it is desired the teeth shall be permanently set.

Another object is to provide a device of this character capable of expansion or contraction to accommodate jaws of different width.

With these objects in view, the invention consists in the production as a new article of manufacture, of a plate having upper and lower faces contoured to receive the articulated ends of upper and lower sets of artificial teeth and to retain such teeth in place, and also in the method whereby such teeth are transferred to trial mouthplates in a position acceptable to the patient, as herein-after described and claimed, and in order that it may be fully understood, reference is to be had to the accompanying drawing, in which:

Figure 1 represents a front elevation illustrative of the means and method whereby upper and lower sets of artificial teeth are transferred from an occlusal plate embody-

ing the invention to trial mouthplates within the mouth of a patient;

Figure 2 is a vertical section taken on the line II—II of Figure 3;

Figure 3 is a vertical section taken on the line III—III of Figure 1;

Figure 4 is a plan view of an occlusal plate embodying the invention; and

Figure 5 is a plan view of a modified form of occlusal plate embodying the invention.

Before proceeding with a detailed description of the invention, it is desired to call attention to the fact that artificial teeth are identified by the manufacturers thereof to guard against mistakes in filling orders, and for the purpose of this invention there will be a correspondingly identified occlusal plate for each complete set of teeth, for example, the plate and teeth of one set may be identified by the character "A," another plate and set by another character, and so on. It is customary for manufacturers to provide a dozen sets, more or less, of artificial teeth, so as to be prepared to meet all conditions which may arise, and it is therefore contemplated that there shall be an occlusal plate for each standard set of artificial teeth produced by manufacturers.

The usual trial plates upon which the teeth are to be temporarily mounted are then applied properly within the mouth as they will be worn. Dental wax or gum or the like will then be caused to adhere to the "gum" margins of the said plates.

The patient's mouth will then be widely opened and the occlusal plate with the teeth mounted thereon will be inserted in the mouth and held in position by the dentist who may at the same time have a mirror properly disposed to permit the patient to note the effect. If necessary, the dentist can shift the plate until the patient is satisfied who then is instructed to close the jaws and thus effect the embedment of the teeth in the wax or gum. After the lapse of a few minutes the mouth can be reopened, this action withdrawing the teeth from the occlusal plate because of the adhesion of the teeth to the gum, and permitting the latter to be removed, when it will be found that the teeth will articulate properly.

The trial plates with the wax and teeth affixed thereto are then removed, and the "waxing up" is finished and the plates are "flasked." The plates are then "invested" 5 in plaster of Paris or the like, and after the same "sets" the trial plates and wax are removed and the teeth are packed with rubber and vulcanized; all steps beginning with the removal of the trial plates with the wax 10 and teeth affixed thereto, being common in the art, and constituting no part of this invention.

Referring now to the drawing in detail, A indicates an occlusial plate for use with an 15 upper set and a lower set of artificial teeth, which may be correspondingly identified or otherwise by the manufacturer, said sets of teeth being identified by the characters *a* and *a'* in the drawing to avoid confusion in 20 the application of the reference characters.

The occlusial plate is produced by any suitable or preferred method by the manufacturer and will preferably be made of metal though it may be made of any other 25 material such as celluloid, hard rubber or any substance having the properties of stiffness and rigidity and which will not soften or become deformed while being handled or from heat or moisture. The plate is shown 30 as substantially yoke-shaped at 1, and provided with a stem or handle portion 2. The yoke portion of the plate will be formed in its upper side with cavities 3 of contour to properly articulate with the biting edges of 35 the upper set of teeth. At its lower side, it will be provided with like cavities 4 for proper articulation with the biting edges of the lower set of teeth, and the cavities will be preferably of sufficient depth to receive 40 and retain the sets of teeth therein against dislocation when handled with a reasonable degree of care, it having been demonstrated in practice that a plate of the character described will retain sets of teeth therein without the necessity of using any adhesive for 45 the purpose, though it is obvious that if desired an adhesive may be employed for temporarily holding the teeth in place. If the use of an adhesive is resorted to, however, it should hold the teeth but lightly so that the connection may be readily broken, as 50 hereinafter explained.

Assuming that a patient to be fitted with 55 artificial teeth has approved a particular set of teeth and that such teeth have been applied to the occlusial plate as explained, trial plates 5 and 6 are fitted in the mouth, and strips of dental gum or the like 7 are pressed against the gum line of the trial plates so 60 as to adhere thereto. The operator then slips the occlusial plate with the teeth applied thereto, as shown, into the patient's mouth and holding the plate by its handle in the position which he deems proper, has 65 the patient partially close the mouth. The

operator can then provide a mirror so that the patient may see the result, and by manipulation of the occlusial plate by applying force upon the handle thereof, can shove all the teeth further into the mouth, draw 70 them forward, or shift them to the right or the left, accomplishing this result obviously without in any way disturbing the articulative relation between the teeth and the plate. When a satisfactory adjustment has been 75 effected the patient will be advised to close the mouth firmly and retain it closed for a few minutes. The closure of the mouth causes the root ends of the teeth to become embedded in the strips of wax, and the connection thus established will, after the lapse of a few minutes, be so firm that upon the reopening of the mouth, the teeth will be withdrawn from the occlusial plate which the dentist will then remove. He will also 80 remove the plates with the gum and the teeth affixed thereto.

As hereinbefore stated, the succeeding steps in the application of the teeth to permanent mouthplates, will be according to 90 common practice and hence are not illustrated or described, but from the foregoing it will be apparent that by the use of an occlusial plate of the character described it is feasible to transfer whole sets of properly 95 articulated teeth to trial mouthplates, and individual adjustment of the teeth is entirely obviated.

To avoid the necessity of providing occlusial plates to accommodate slight variations in the width of the jaws, plates may be made in two sections frictionally pivoted together as at 8 on the medial line L so that 100 pivotal adjustments of the plate to more widely separate the molars shall not appreciably change the spacing of the front teeth at opposite sides of such line, it being obvious that a very slight adjustment one way or the other, will permit the plate to be 105 used on wide or narrow jaws.

It will be apparent from the drawing and description that the invention is susceptible of modification in minor particulars without departing from the principle of construction and mode of operation involved, and I therefore reserve the right to make 110 all changes falling within the spirit and scope of the appended claims.

I claim:

1. A dental occlusial plate composed of a pair of like members hinged together and having their upper and lower faces contoured for proper articulation respectively with articulated upper and lower sets of teeth.
2. A dental occlusial plate of stiff material composed of two like members hinged together and provided with cavities in its upper and lower sides conforming to and adapted for receiving and holding upper 130

and lower sets of properly articulated teeth being adjustably connected so that the plate at the biting ends thereof. as a whole can be widened or narrowed to accommodate jaws of different width. 10

3. A dental occlusial plate consisting of two sections, each section being provided in 5 its upper and lower faces with cavities conforming to and adapted for receiving and holding corresponding teeth; said sections

In witness whereof I hereunto affix my signature.

JEPHTA G. HOLLINGSWORTH.
